INVENTOR

Harry H. Klein.
BY *Benjamin Rosen.*
ATTORNEY

UNITED STATES PATENT OFFICE.

HARRY H. KLEIN, OF NEW YORK, N. Y.

HAIR WAVER.

Application filed September 1, 1921. Serial No. 497,693.

To all whom it may concern:

Be it known that I, HARRY H. KLEIN, a citizen of the United States, and resident of city of New York, in the county of New York and State of New York, have invented certain new and useful Hair Wavers, of which the following is a specification.

This invention relates to dress-weighting, or those devices, sometimes designated "weighted tape," that are utilized in connection with women's wearing apparel, along the lower edges of which they are sewed on for weighting down the garment and presenting thereto a taut appearance.

The principal object of my invention is to provide simple, inexpensive, conveniently and economically manufacturable, conveniently utilizable, strong, durable, efficient, and improved dress weighting.

Another object of my invention is to provide a method for manufacturing this new dress weighting, which method may be employed for manufacturing articles having many of the characteristics of the dress weighting herein, but which manufactured articles may be utilized for various other purposes, non-analogous to that of dress weighting as will be hereinafter seen.

Other objects and advantages will herein-after appear.

In the accompanying drawings,—

Fig. 1 is an elevation showing a step in the process of manufacturing this dress-weighting.

Fig. 2 shows an elevation of the completed dress weighting, and also illustrates other of the steps in the process of manufacturing this dress-weighting.

Fig. 3 is a cross-sectional end elevation, in an enlarged scale, of the dress-weighting shown in Fig. 2.

Fig. 4 is an elevation illustrating the applicability of the process herein to the manufacture of hair wavers, and shows the completed hair wavers and also the steps in the process for manufacturing the hair wavers.

Fig. 5 is a cross-sectional end elevation in an enlarged scale, of the waver shown in Fig. 4.

Fig. 6 is a cross-sectional end elevation, showing a modification of the weighting.

The dress weighting 1 comprises a series or plurality of weights 2 mounted upon a string or cord 3, and a wound thread 4 cov-

ering the weights 2 as well as the stretches 55 of the cord 3 between the weights 2. In the production of this dress-weighting the series of weights 2 are placed upon the cord 3 equidistantly, and the covering 6 for the weighting is then formed by means of winding the thread 4 around the weights 2 and around the cord 3 in a continuous manner, as shown in Figs. 2, 3. The weights 2 may be made of any suitable substance and configuration, but are preferably made of lead, 60 and preferably are of the double-conical configuration here shown. The cord 3 may consist of an elongated strip of any suitable flexible material and of any cross-sectional shape, but preferably it consists of a fibrous 70 cord of a circular cross-sectional shape, as here shown. The thread 4 may consist of any suitable filamentary substance of any cross-sectional shape, but it is here shown as consisting of any common fibrous thread of 75 preferably a circular cross-sectional shape. As here shown, each of the weights 2 is provided with a longitudinal slot 7, which extends from the periphery of the weight down to the locality of the longitudinal axis of the 80 weight, and as each weight 2 is placed upon the cord it is slid thereover so that the cord 3 passes through its slot 7 and is lodged therein in alignment with the longitudinal axis of the weights, as shown in Fig. 3. 85 Said slot may be of the same width as the diameter of the cord 3, so that the latter merely rests freely against the bottom wall of the slot, or this slot may be made narrower, whereby the cord 3 will bind therein 90 and in this manner secure each weight of the series thereto, preliminarily to winding the thread 4 thereover to form the covering 6.

When the dress-weighting is thus completed in any indeterminate length, any 95 section or length thereof may be severed from the remainder and utilized for required purposes. It will be noted that, if desired, the weights 2 may be made flattened, of enlarged compass, and of any appropriate circumferential shape; in which case they may be cut off individually from the remainder of the connected series of weights, and utilized for sewing on individually to the corners, or at intervals along 100 the lower edges, of garments. It will be evident that when the weighting is manufactured in the form of this type it may be

either manufactured in the form of tape, or in the form of individual weights. Or the same may be manufactured as tape-weighting and then severed between the weights 2 5 to constitute individual weighting and sold as such, or the same may be sold in the form of tape weighting and the purchaser may then sever the tape between the weights into individual weighting.

10 In the modification shown in Fig. 6, the weights 2 are mounted upon a plurality of cords 3, which pass through respective slots 7 formed in the side of each weight, and one of the advantages of this modification 15 is that when the thread 4 is being wound around the weights and the cords 3 the latter retain the weights against any tendency toward lateral or rotational dislocation.

It is found that the process and principles underlying this invention may be 20 adapted and utilized for the production and manufacture of articles other than dress-weighting and for this reason the invention herein is claimed as an article of manufacture per se, in addition to being claimed 25 as dress weighting.

Thus, in Figs. 4 and 5 is shown the applicability of this invention to the production of hair wavers. The waver 8 comprises a 30 core 9 mounted upon or placed adjacent to or against a tape 10, and a wound thread 11 covering the core 9 and tape 10 as well as the terminals 12 of the tape projecting beyond the extremities 13 of the core 9. In 35 the production of these wavers a plurality of cores 9 are placed equidistantly upon a tape 10 of indeterminate length, and the covering 14 for the wavers is then formed by means of winding the thread 11 around 40 the cores 9 and tape 10, and around the connecting tape-portions 15 between the adjoining cords 9, in a continuous manner as shown in Figures 4, 5. The cores 9 may be made of any suitable substance and may be 45 of any suitable well known construction which would give it required pliability, but as here shown are made of lead strips. The tape 10 may consist of an elongated strip of any suitable flexible material and of any 50 cross-sectional shape, but preferably it consists of the fibrous textile tape of flattened cross-sectional shape here shown. The thread 11 may consist of any suitable filamentary substance of any cross-sectional 55 shape, but it is here shown as consisting of any common fibrous thread of preferably a circular cross-sectional shape. As here shown, the tape 10 may be merely placed against the core 9 and the thread 11 wound 60 around both, but if desired the core 9 may be secured by some suitable positive means to the tape 10, preliminarily to winding the thread 11 therearound to form the covering 14. Thus, for example, the cores 9 may be 65 secured to the tape 10 in the manner shown

in Figs. 3 or 6 and described in connection with those forms. Or, if desired, an adhesive may be applied to the tape 10 during the manufacturing process, by which means the securing of the cores 9 to the tape 10 70 may be effected, and which would also act as a binder for the thread 11 during the winding process, and would act to bind additionally and permanently the thread 11 to the tape 10 and core 9. After the manu- 75 facturing of the indeterminate plurality of hair wavers is thus completed they may be severed at their connecting places 15, to constitute the individual wavers 8 as utilized for hair curling.

80 Variations may be resorted to within the scope of the invention, and portions of the improvements may be used without others.

Having thus described my invention, I 85 claim:—

1. The method of producing an article of manufacture consisting in connecting a plurality of bodies to each other, then winding a thread transversely around said bodies and connecting means, and then severing said 90 connecting means.

2. A hair waver having the combination of a core, a strip of material placed against said core and projecting beyond its terminals, and a covering of wound thread enveloping said core and strip and being secured to said strip.

3. A hair waver having the combination of a core, a strip of material placed against said core, and a covering of wound thread 100 enveloping said core and strip and being secured to said strip.

4. A hair waver having the combination of a core, a strip of material placed along said core and secured thereto, and a covering 105 of wound thread enveloping said core and strip and being secured to said strip.

5. A hair waver having the combination of a core, a strip of material placed along said core and secured thereto at its axis, and 110 a covering of wound thread enveloping said core and strip and being secured to said strip.

6. A hair waver having the combination of a core, a strip of material placed against 115 said core at its axis, and a covering of wound thread enveloping said core and strip and being secured to said strip.

7. An article of manufacture having the combination of a core, a strip of material placed against said core and projecting beyond its terminals, and a covering of wound thread enveloping said core and strip and being secured to said strip.

8. An article of manufacture having the 125 combination of a core, a strip of material placed against said core, and a covering of wound thread enveloping said core and strip and being secured to said strip.

9. An article of manufacture having the 130

combination of a core, a strip of material placed along said core and secured thereto, and a covering of wound thread enveloping said core and strip and being secured 5 to said strip.

10. An article of manufacture having the combination of a core, a strip of material placed along said core and secured thereto at its axis, and a covering of wound thread 10 enveloping said core and strip and being secured to said strip.

11. An article of manufacture having the combination of a core, a strip of material placed against said core at its axis, and a 15 covering of wound thread enveloping said core and strip and being secured to said strip.

12. The method of producing hair wavers consisting in placing a plurality of cores 20 along and against an elongated strip of material, then winding a thread transversely around said cores and strip to form a covering for the cores, and then severing said strip and covering between said cores.

25. 13. The method of producing hair wavers consisting in placing a plurality of cores along an elongated strip of material and securing them thereto, then winding a thread transversely around said cores and strip to 30 form a covering for the cores, and then severing said strip and covering between said cores.

14. The method of producing hair wavers consisting in placing a plurality of cores at 35 their axes along a strip of material and securing them thereto, then winding a thread transversely around said cores and strip to form a covering for the cores, and then severing said strip and covering between 40 said cores.

15. The method of producing articles of manufacture consisting in placing a plurality of cores along and against an elongated strip of material, then winding a 45 thread transversely around said cores and strip to form a covering for the cores, and

then severing said strip and covering between said cores.

16. The method of producing a hair waver consisting in taking a core, placing a strip 50 of material of greater length than the core thereagainst, and then winding a thread transversely around said core and strip to envelope them and securing said thread to said strip. 55

17. The method of producing a hair waver consisting in taking a core, placing a strip of material against said core, and then winding a thread transversely around said core and strip to envelope them and securing said 60 thread to said strip.

18. The method of producing an article of manufacture consisting in taking a body, placing a strip of material of greater length than the body thereagainst, and then winding a thread transversely around said body and strip to envelope them and securing said 65 thread to said strip.

19. The method of producing an article of manufacture consisting in taking a body, 70 placing a strip of material against said body, and then winding a thread transversely around said body and strip to envelope them and securing said thread to said strip.

20. An article of manufacture having the 75 combination of a plurality of elongated strips of material, a body placed along and against said strips, and a covering of wound thread enveloping said body and strips.

21. The method of producing an article 80 of manufacture consisting in placing a plurality of bodies along and against a plurality of elongated strips of material, then winding a thread transversely around said bodies and strips to form a covering for the 85 article, and then severing said strip between said bodies.

Signed at the city of New York, in the county of New York, and State of New York, this 31st day of August, A. D. 1921. 90

HARRY H. KLEIN.
